United States Patent Office.

THOMAS WILLIAM WEBLEY, OF BIRMINGHAM, ENGLAND.

Letters Patent No. 65,783, dated June 11, 1867.

IMPROVEMENT IN BREECH-LOADING FIRE-ARMS.

The Schedule referred to in these Letters Patent and making part of the same.

TO ALL TO WHOM IT MAY CONCERN:

Be it known that I, THOMAS WILLIAM WEBLEY, of 84 Weaman street, Birmingham, in the county of Warwick, England, a subject of the Queen of Great Britain, have invented or discovered new and useful "Improvements in Breech-Loading Fire-Arms;" and I, the said THOMAS WILLIAM WEBLEY, do hereby declare the nature of the said invention, and in what manner the same is to be performed, to be particularly described and ascertained in and by the following statement thereof; that is to say—

This invention has for its object improvements in breech-loading fire-arms, and is applicable to that class of fire-arms in which the breeches of the barrel or barrels are opened to receive cartridges by turning down the barrels on a horizontal axis that is at right angles to their length and at a short distance from their breech ends, so that their breech ends are raised up above the breech-piece. The barrels when in position for firing have in some cases been secured by a catch known as the Lefaucheux or double-grip action catch, which is composed of a locking bolt on the axis of a lever which is formed to fit against the trigger-guard. My invention consists in applying a spring to the locking bolt of this action to cause the gun to be self-locking when closed to force the barrels home. I prefer to apply the spring in such a manner as to cause the lever-handle of the bolt after it has been moved in either direction beyond the centre of its travel to fly over to completely open or completely close the catch. By this means the gun is made handier to open, and self-locking when closed, by forcing the barrels home. A spring so applied is shown in the drawings hereunto annexed. I would, however, have it understood that I do not confine myself to this arrangement, as other modes of applying a spring may be adopted, as, for example, a portion of the advantage derived from this arrangement may be obtained by so combining the spring with the locking bolt as to make it self-locking only in place of acting, both to completely open as well as completely to close the catch. The arrangement shown is, however, the one that I prefer to employ.

Figure 1 shows a longitudinal section of so much of a breech-loading double-barrel gun as is necessary to illustrate my invention.

Figure 2 is an under side view of the breech-piece, the locking belt or catch being removed; and

Figure 2 is an under side view of the breech-piece, the locking bolt, &c.
 Figure 3 is a plan view of the locking bolt separately.
 a are the barrels, capable of turning on the pin b, carried by the projection c' on the under side of the breech-piece c, as is usual. d is the cylindrical locking bolt, provided with a lever-handle, d', and turning on the pin e, carried by the projection c' of the breech-piece. f is a lump on the under side of the barrels, in which is formed the slot or recess into which the locking bolt engages, small projections f' on opposite sides of the mouth of the slot being received into spiral grooves formed around opposite sides of the periphery of the locking bolt in the ordinary manner. g is a bent spring, received in a vertical recess in the centre of the back of the breech-piece. One end of the spring is fixed by screws to the breech-piece, and its other end enters a hole in the back of a connecting-rod or slide, h, on the forward end of which is a pin that enters a hole, k, in the locking bolt, this hole being formed at the bottom of one of the spiral grooves in the locking bolt, as seen at figs. 1 and 3. When the locking bolt is turned by its lever-handle to release the barrels, the spring is first pressed back by the rod h until the pin has passed the centre line between the end of the spring and the pin e on which the locking bolt turns; the spring then presses the rod h forwards, and aids in turning the locking bolt until the barrels are released and free to turn on their pin joint. When the barrels are again turned up to close the gun, the projections f' on the lump below the barrels, by acting on the spiral grooves in the locking bolt, turn the bolt round towards its former position, as is usual, but in place of having by hand to complete the motion of the lever the spring g presses forward the rod h and forces round the bolt, so as completely to lock the gun.

Having thus described the nature of my invention, and the manner of performing the same, I would have it understood that what I claim is the applying a spring to the locking bolt of what is known as the Lefaucheux or double-grip action catch of breech-loading fire-arms, so as to cause the gun to be self-locking when closed by forcing the barrels home.

THOS. W. WEBLEY.
